UNITED STATES PATENT OFFICE.

CHARLES F. COLE, OF HUNTINGTON, WEST VIRGINIA.

BOILER STAND.

Application filed April 9, 1923. Serial No. 630,694.

My invention consists of a new and improved stand for vertically disposed hot water boilers.

One of the objects which I have in view is the provision of a device, for the purpose described, which is adjustable so as to accommodate itself to various diameters of boilers, and also which will permit of adjusting the boiler to any elevation above the floor which may be desired.

Another object which I have in view is the provision of a boiler stand which will provide a more firm and stable support for the boiler, and which cannot be readily knocked or forced laterally from position.

Adjustable boiler stands which may be arranged to accommodate boilers of different diameters have been patented; and also stands which will permit of varying the elevation of the boiler, but such stands have been of the central or axial pedestal type, and as far as my knowledge goes such stands have never been capable of adjustment both to different boiler diameters and elevations.

A cardinal objection to the axial pedestal type of stand is its lack of stability, the pipe connections being usually relied upon to steady the boiler and always taking the strain and torque in case the boiler tips or receives a lateral thrust. Again, if the floor or surface on which the boiler is erected is uneven or not truly horizontal, the boiler is not firmly supported nor will it be vertical, all of which makes the boiler insecure and puts a dangerous strain on the piping. Again it requires at least two workmen to erect a boiler on a pedestal stand, one being required to support and retain the boiler in its vertical position, while the other workman connects the piping to the tank.

My improved boiler stand is characterized by the provision of three or more legs which support the boiler at its perimeter at equally spaced points so that the boiler is supported against tipping, and said legs are vertically extensible so that the boiler may be supported at any desired elevation from the floor, and each leg is individually extensible so that the boiler may be readily supported in a truly vertical and level position even on an irregular surface or floor or on a surface or floor which is not horizontal.

The legs are connected and braced so that they cannot be accidentally knocked or shifted out of position; and means are provided whereby they may be adjusted toward or

away from the common center or axis of the boiler so as to accommodate boilers of different diameters.

Means are also provided for bracing the legs to prevent their being forced out of their vertical position by a lateral kick or blow.

I prefer to form my improved legs of sheet metal of suitable gauge which is bent up into cylindrical form and fastened.

Other novel features of construction and arrangement of parts will appear from the following description.

In the accompanying drawings, which are however merely intended to illustrate a practical embodiment of the principles of my invention without limiting the scope of the latter to the construction shown, Fig. 1 is an elevation showing a hot water boiler supported by a stand embodying the principles of my invention; Fig. 2 is an enlarged elevation of one of the legs; Fig. 3 is a top plan view of the same; Fig. 4 is a broken section of the leg taken along the line IV—IV in Fig. 3; Fig. 5 is a top plan view of the connecting member; Fig. 6 is a diametric section of the connecting member showing a modification, and Fig. 7 is a perspective of one of the struts or braces.

The following is a detailed description of the drawings.

The boiler A is supported by three or more extensible legs B, the bottom flange 1 of the boiler resting directly on the tops of the legs which latter are equally spaced apart around the axis of the stand.

The legs are each formed of two elements, an upper element B' which is tubular and telescopes down over the lower element B² which is also shown as tubular but which may be solid if desired.

The two elements are in meshed engagement. Thus I have shown the spiral threads 2 of the lower element B² screwed up into the threads 3 of the upper element B'. Thus the length of each leg may be adjusted so that the tops of the legs will be in the same horizontal plane, thus supporting the tank in a truly vertical position, and at any desired elevation. The lower leg element B² is provided with a laterally extended foot to maintain a firm bearing on the ground or floor. Thus I have shown a sleeve 4 which may be forced up into the interior of the element B² and which is provided with a horizontally extended annular flange 4' forming the foot of the leg. The flange 4' may be pierced with

screw holes 5 so that the leg may be firmly anchored to the floor.

The leg elements may be of pipe or other tubing. I prefer to form the same by bending up into tubular form sheet metal of sufficient gauge and stiffness, welding or otherwise securing the edges of the sheet to form a permanent tube. The threads 2 and 3 may then be spun in the metal or the same may be pressed or rolled in the flat blanks before the latter are bent up into tubes. The upper end of the lower element B² is preferably unthreaded, fitting the upper unthreaded portion of the upper element B' with sufficient looseness to give clearance for connecting the bracing struts, as will be described.

The upper end of the blank from which the upper leg element B' is formed is provided with an integral tongue 6 which is bent over horizontally to close the upper end of the leg against the entrance of water which might cause rusting within the leg. The upper end of said blank is also provided with a longer tongue which is bent over into a horizontal position over the tongue 6 and which extends at right angles to the leg to form the bracket 7 by means of which the top of the leg is anchored to the center member C. At its outer end or base said tongue 7 is cut to form the spur 8 which projects upwardly to bear against the outer side of the flange 1 of the tank A. At either side the bracket 7 is notched, as at 9, to provide clearance for the spurs 10 cut from the tongue 6 and bent upwardly so as to engage the flange 1 of the tank A from within. Thus there can be no lateral movement between the tank and the legs upon which its bottom flange 1 rests.

The bracket 7 is supported in its position, as by a diagonal strut 11 extending between the upper leg member and the end of the bracket.

I show a convenient type of strut formed by longitudinally folding a narrow strip of sheet metal. The upper end of the fold is split to form a pair of tongues 12 which are inserted through a rectangular and snugly fitting hole 13 in the outer end of the bracket 7. The tongues are of less width than the strut thus forming the shoulder 14 which bears upwardly against and supports the bracket 7, while the tongues protruding through the hole 13 are upset and bent down flat to lock the end of the brace to the bracket. The hole 13 is positioned in a depression 15 in the bracket, so that the bent down tongues do not project above the general plane of the bracket. The lower end of the strut is provided with a pair of laterally extending ears 16 which are inserted through a slotted hole 17 in the wall of the upper leg member B' and are bent flat against the interior wall of the brace so as not to interfere with the upper end of the lower leg member B². The lower end of the strut is also provided with shoul-

ders 18 which bear against the exterior of the leg member B'. If desired the struts may be riveted to the legs.

Any other suitable manner of supporting and bracing the bracket 7 may be used.

The center member C is shown in the form of a metal ring, either stamped or cast, as may be desired. The function of the member C is to connect the upper ends of the several legs together, and therefore said member need not be annular in shape, but is so shown as its preferred form. The member is shown provided with a central aperture 19, which economizes material and also enables the use of a bottom burner for heating the tank if the same be preferred to the water coil type of heater now in more general use. If desired the central aperture of the member C may be provided with a downwardly flaring flange C' which will act as a funnel or directing flue for the gas flames of a burner.

Convenient means are provided for securing the legs to the center member, said means permitting adjustment of the position of the legs relative to the center of the connecting member which is the axis of the stand.

Thus I have shown the member C provided with equally spaced apart groups of radially arranged holes 20 into which are upwardly inserted the spurs 21 cut from the material of the brackets 7, the ends of the spurs being bent down snug against the top surface of the member C. Thus the legs are anchored to the center member and cannot be spread apart or their relation altered while so attached.

I have shown the brackets 7 provided with a pair of longitudinally aligned spurs 21 and the group of holes 20 in the member C spaced the same distance apart as the spurs 21 but the number of holes in each group exceeding the number of spurs. Thus by engaging the spurs with either the outermost pair of the three holes 20, or the innermost pair of the same, the legs may be set farther out from or nearer to the axis of the stand, thus properly positioning the legs relative to the flange 1 of the particular diameter of boiler to be supported. The diameters of boilers most in use are twelve and fourteen inches so I have shown the center member C arranged for two leg adjustments, but by increasing the number of holes 20 in each radial group any desired number of adjustments may be provided for.

To further brace the legs against lateral or side thrust or displacement I may provide additional struts 22, shown in dotted lines in Fig. 2, similar to the struts 13, and having their lower ends engaged in holes 23 in the sides of the upper leg members B' at either side of the hole 17 and having their upper ends engaged in holes 24 in the member C at either side of the bracket 7. To permit of moving the legs inwardly or outwardly to adjust the stand to various diameters of boilers,

two or more sets of holes 24, depending upon the number of adjustments to be provided for, are provided in the member C.

It is evident from the foregoing that my improved stand amply provides for rigidly supporting boilers of different diameters at various elevations, and that the boilers are stably supported in a truly vertical position. It is also evident that any unevenness or inclination in the floor may be readily compensated for without impairing the vertical position of the boiler. It is further evident that the boiler may be erected by a single workman, since he can first assemble and erect the stand and then lift and mount the boiler thereon without aid, thus saving both time and expense.

Hot water boilers are frequently installed in basements and cellars having relatively low ceilings, so that the conventional type of stands are unsuitable.

In such case my improved stand works a decided advantage as the boiler may thus be set low enough to clear the ceiling and to give ample clearance for the pipe connections.

It is further evident that the legs cannot be displaced by a lateral thrust or blow and that no strain or torque will be conveyed to the piping.

The boiler rests on the legs, giving a direct vertical thrust without torque.

No bolts or screws are required to set up the stand and mount the boiler thereon. This greatly facilitates the operation of installing or removing a boiler, and reduces the time and labor required.

My improved stand is very convenient for shipping and handling, as it may be packed in a pasteboard carton or other suitable container, and may be distributed to the job in packed condition. This facilitates handling and distribution from manufacturer through the jobbers and plumbers to the consumer.

Although for the sake of clearly illustrating the principles of my invention I have de-

scribed in detail the embodiment of the same shown in the drawings, I do not wish to limit myself thereby but claim broadly:—

1. A boiler stand having a series of equidistantly spaced legs, each leg comprising a vertical tubular post having its upper end longitudinally split to provide a pair of tongues, one of said tongues being bent to close the upper end of the tubular post and the other of said tongues being lapped over the closed end of the tube and projecting to one side thereof to provide a supporting arm for the lower edge of the boiler.

2. In a stand for supporting a boiler in a vertically disposed position, the combination of a plurality of tubular legs equally spaced apart and having integrally formed tongues extending at right angles to the longitudinal axis of the legs for supporting the boiler, a retaining lug projecting upwardly from the top of each leg and adapted to be positioned against the outer face of the flanged bottom edge of the boiler, a pair of relatively spaced lugs positioned inwardly of each retaining lug and adapted to be disposed against the inner surface of the flanged bottom edge of the boiler, and a disc like ring secured to the top of the tongues for holding the legs in fixed relation to each other.

3. In a stand for supporting a boiler in a vertically disposed position, the combination of a plurality of tubular legs equally spaced apart and upon which the flanged bottom edge of the boiler rests, a plurality of radially spaced lugs projecting upwardly from the top of each of said legs and between which the flanged bottom edge of the boiler fits, a tongue on the top of said legs having upwardly struck spurs, and a disc like ring on the tongues provided with apertures for receiving said spurs for retaining the legs in fixed relation to each other.

Signed at Pittsburgh, Pa., this 5th day of April, 1923.

CHARLES F. COLE.
